UNITED STATES PATENT OFFICE.

FREEBORN COGGESHALL, OF NEWPORT, RHODE ISLAND.

TRAFFIC-STAND.

1,174,395.

Specification of Letters Patent.

Patented Mar. 7, 1916.

Application filed July 7, 1915. Serial No. 38,611.

To all whom it may concern:

Be it known that I, FREEBORN COGGESHALL, a citizen of the United States of America, and resident of Newport, in the county of 5 Newport and State of Rhode Island, have invented certain new and useful Improvements in Traffic-Stands, of which the following is a specification.

This invention relates to stands which 10 are especially adapted for use by policemen or traffic officers at the intersection of streets where they have to be stationed for directing traffic, the said invention being designed as a protection for the said traffic officers.

15 It is the purpose of the inventor to shield the occupant of the stand from sun during the heated terms of the year or from rain and cold winds, the said invention affording free movement of the body so that the 20 officer may turn for the purpose of giving signals in directing traffic.

A further object of this invention is to 25 provide a shield as a guard against rain or cold winds, said guard having means for its attachment or removal from the permanent structure of the stand, the said stand being furthermore provided with means for removably holding an umbrella or canopy.

30 With the foregoing and other objects in view, the invention consists in the details of construction and in the arrangement and combination of parts to be hereinafter more fully set forth and claimed.

35 In describing the invention in detail, reference will be had to the accompanying drawings forming part of this specification, wherein like characters denote corresponding parts in the several views, and in 40 which—

Figure 1 illustrates a view in perspective showing a stand embodying the invention, a part being broken away; Fig. 2 illustrates a sectional view transversely of the stand 45 with the mat omitted; Fig. 3 illustrates a detail view of the base of the stand and the floor thereof showing a device for fastening the lower end of the shield or closure; and Fig. 4 illustrates a plan view

50 of a fragment of the closure showing the fastener thereof adapted to coöperate with the fastener on the base.

In these drawings 5 denotes the base sills or frame, 6 a floor thereon, said floor being 55 made up of sections having spaced relation to one another to afford drainage there-

through and 7 a mat, preferably of rubber located on the floor on which the occupant may stand.

There is a series of sockets 8 with flanges 9 secured to the floor in any appropriate manner as by the fastenings 10 and these sockets engage and retain the lower ends of the posts 11, 12 and 13, the latter of which has an inwardly extending angular 60 portion 14 intermediate its length. The upper ends of the posts 11 and 12 have fittings 15 and the upper end of the post 13 has a fitting 16 by which a curved rail 17 is secured to the said posts, the said 65 posts and rail constituting a frame-like structure for the support of a shield or curtain 18, preferably of flexible fabric, which is held by the posts and rail at its upper portion and by fastenings at its lower 70 portion to form a housing for the protection heretofore mentioned. I prefer that the said shield or curtain shall be provided with attachments, such as straps 19 75 encircling the portions of the frame as shown in Fig. 1 of the drawing, whereas the lower end of the curtain has reinforcing plates 20 provided with apertures 21 to receive the latches 22, located preferably on the edges 80 of the floor so that the shield may be so held as to prevent wind from passing over the floor of the stand. The frame 5 is polygonal and wind cannot pass to the interior of the frame under the floor so that when the shield is in place, the occupant 85 of the stand is well guarded or protected. 90

The socket 23 is anchored to the floor and constitutes a holder for the umbrella or canopy stick 24 and the said socket 23 may have a binding screw or pin 25 therein to prevent the umbrella stick from leaving the socket under pressure of wind or the like. 95

As seen in the drawing, the stand is provided with a clip 26 by which the mirror 27 is adjustably held so that the occupant of the stand may not only observe that traffic which is in front of him, but also the traffic which is approaching from the sides or rear. 100

I claim—

1. In a traffic stand, a base, a floor thereon, sockets secured to the floor, posts in the sockets, a curved rail, means for securing the curved rail to the posts, a shield comprising a flexible fabric, means for securing the shield to the posts and rail, 110

2
apertured plates on the shield near its lower end and devices on the floor extending through the apertured plates for holding the shield in place, a socket anchored to the plate, and a canopy support in said socket.

2. In a traffic stand, a base, a floor thereon, sockets secured to the said floor, posts in the sockets, a curved rail, means for securing the curved rail to the posts, a shield comprising a flexible fabric, means for securing the shield to the posts and rail, apertured plates on the shield near its

lower end, devices on the floor extending through the apertured plates for holding the shield in place, a socket anchored to the plate, a canopy support in said socket, a mirror, and means secured to the rail for supporting the mirror.

In testimony whereof I hereunto affix my signature in the presence of two witnesses.

FREEBORN COGGESHALL.
